UNITED STATES PATENT OFFICE.

CHARLES T. GROSJEAN, OF NEW YORK, N. Y., ASSIGNOR TO TIFFANY & CO.,
OF SAME PLACE.

DESIGN FOR A HAIR-BRUSH.

SPECIFICATION forming part of Design No. 17,422, dated June 28, 1887.

Application filed March 18, 1887. Serial No. 231,451. Term of patent 7 years.

To all whom it may concern:

Be it known that I, CHARLES T. GROSJEAN, a citizen of the United States, and a resident of New York city, in the county and State of New York, have invented and produced a new and original Design for Hair-Brushes, of which the following is a specification, reference being had to the accompanying drawings, forming part thereof.

10 Figure 1 is a top or plan view of my newly-designed hair-brush. Fig. 2 is a side view of the same, and Fig. 3 is an end view of the same. Fig. 4 shows the design applied to a military hair brush. Figs. 1^a, 1^b, 1^c, 1^d are sectional views on the lines a a, b b, c c, and d d of Fig. 1, respectively.

15 My design has special reference to the body part of the brush, as distinguished from the handle, so that various forms of handles may be used without departing from my invention, or the brush can be made without a handle; as in the military brush shown in Fig. 4.

Fig. 1 shows my design applied to a brush having a handle.

20 The design consists in the shape or configuration of the body of the brush so far as it relates to the outline or exterior curves of the brush-body as they appear in a top or plan view or a longitudinal sectional view.

25 The character and effect of the present design are entirely new and different from those of any design based upon the oval, the elliptical, or the rectangular.

30 This design consists in the outline of the brush, as shown in Figs. 1 and 4. The side lines of the brush curve but slightly at their middle portions and during the greater part

of their length; but at their ends the curve is deepened so as to meet the curving ends of the top and bottom lines. The top line of the 40 brush is also curved slightly and delicately, and the bottom line is formed substantially as the top line, except so far as it may be modified to meet the lines of a handle.

45 This design gives a peculiar and subtle richness and fullness to the body of the brush, such as cannot be obtained by any variety of oval or elliptical forms, and yet avoids the stiffness and abruptness of any rectangular form. The design combines, therefore, the 50 completeness of the rectangular form with a gracefulness and beauty superior to the oval or elliptical, and produces an artistic motive or effect distinct from anything hitherto known.

55 As shown in the drawings, the lower end of the handle is curved in substantially the same manner as the upper end of the brush-body; but this form of the handle is not essential to the first part of my invention, which relates to the brush-body.

What I claim as new, and desire to secure by Letters Patent, is—

60 The design for hair-brushes, substantially as shown and described, consisting of the outline 65 of body and handle, the sides and upper end of the body being curved but slightly, with sharp curves at the corners, and the lower end of the handle being curved like the upper end of the body.

CHARLES T. GROSJEAN.
